UNITED STATES PATENT OFFICE.

JAMES WOLSTENCROFT AND WILLIAM H. SOLEY, OF PHILADELPHIA,
PENNSYLVANIA.

ELECTRICAL TARGET-TRAP.

SPECIFICATION forming part of Letters Patent No. 428,030, dated May 13, 1890.

Application filed August 14, 1889. Serial No. 320,724. (No model.)

To all whom it may concern:

Be it known that we, JAMES WOLSTENCROFT and WILLIAM H. SOLEY, citizens of the United States, and residents of the city and county of Philadelphia, State of Pennsylvania, have invented a new and useful Improvement in Throwing-Traps, of which the following is a true and exact description, due reference being had to the drawings which accompany and form part of this application, and in which similar letters denote similar parts.

Our invention relates more specifically to improvements in the throwing-arm and mechanism by which it is locked in position and released to throw the clay pigeon; also, in certain novel mechanism for operating the clutch to release the clay pigeon, and also in novel means for connecting the throwing-arm with the base, so that the position of the throwing-arm may be adjusted horizontally.

In the drawings, Figure 1 is a plan view of the throwing apparatus and stand or base with clutch closed. Fig. 2 is a front elevation of the throwing apparatus and stand or base. Fig. 3 is a transverse section on line $x-x$, Fig. 2. Fig. 4 is a cross-section on line $y-y$, Fig. 2. Fig. 5 is a detached view of the chuck, showing clutch open. Fig. 6 is a plan view of the clay pigeon. Fig. 7 is a sectional view of clay pigeon.

A represents the throwing-arm, pivoted at a to the frame B. Connected to the end of this throwing-arm at a' is the coil-spring C, which is connected at its other end c to the frame B. At the outer end of the throwing-arm A is the chuck D, pivoted to said arm at e , which consists of jaws d d' , connected together by the spring d^2 . On these jaws are the lugs d^3 , d^4 , and d^5 , which are made of soft material; also, the curved lug d^6 , preferably pivoted to the jaw d of the chuck. These jaws are pivoted together at d^7 .

E is a cam-shaped projection, which is connected to the throwing-arm by the screw or bolt e , said bolt being connected to the throwing-arm and passing through the slot e' in the projection of the cam e , so that the cam

may be adjusted. This cam has a curved portion e^2 and the angular or projecting portion e^3 .

Projecting from the end of the jaw d' is the cam F, which rests against the cam E. When the throwing-arm is released, as will hereinafter be described, the arm A swings around, carrying with it the chuck, which swings on its pivot-connection, and the cam on the jaw d' rides on the curved portion of the cam E until it assumes the position shown in Fig. 5, opening the jaws, when the clay pigeon or other article held in the chuck is released and thrown. When the throwing-arm is brought back again to the position shown in Fig. 1, the chuck is moved back from the position shown in Fig. 5 by hand until it reaches the position shown in Fig. 1, compressing the spring d^2 , the notched portion of the cam F striking the projection e^3 of the cam E, which closes the jaws until they assume the position shown in Fig. 1. The screw or bolt e , working in the slot e' , enables the cam E to be adjusted, so that the jaws of the chuck may be open at different parts of the movement of the throwing-arm.

The throwing-arm is normally secured in position by means of the latch G, having the bifurcated projecting ends g g' . This latch is pivoted to a projection g^2 from the frame B by the pivot g^3 . The bottom of this latch has the tail-piece g^5 , upon which is the projecting pin g^4 .

Pivoted to the projection H from the frame B is the arm h , which is pivoted at h' .

Surrounding the rod h^4 , which is secured to a projection h^2 from the projection H, is the coil-spring h^3 . This spring is in such a position that when the pivoted arm h is down it presses against the spring. Connected to the latch G is the spring g^6 . The spring h^3 normally holds the pivoted arm h up, the arm h holding the latch G in the position shown in Fig. 3. When the arm h is pulled down on its pivot-point h' , the latch G is released and the spring g^6 causes it to move backward and the throwing-arm goes into action. When it is desired to set the trap again, the throwing-

arm is pushed forward until it strikes the end g of the latch, which pushes the latch forward on its pivot-point until said latch strikes the arm h , which forces said arm down against the spring h^3 . This continues until the throwing-arm passes beyond the end g and strikes the guide J when the tail-piece g^5 of the latch has passed beyond the end of the arm h , the pin g^4 holding the arm h down, while the end g^5 , resting against the end of the arm h , locks the latch and holds the arm A in fixed position and the spring g^3 is put in tension. The reverse movement of the throwing-arm when the apparatus is in this position will have no effect upon the latch, but when the pivoted arm h is pulled down either by the string I , or if said arm h is connected to the armature K of the magnets K' , said magnets being supported on the projection h^2 , and being in connection with the battery L by means of the circuit M . This circuit M may be an open circuit, and a key N , placed at any point, will close the circuit, so that the magnets are affected by the current and the armature is drawn down, carrying with it the pivoted arm h , which allows the tail-piece g^5 to be released, and the spring g^6 moves said latch backward, allowing the throwing-arm to act by means of the spring C .

O is the base or stand of the throwing apparatus, which has the projection o . Surrounding this projection o is a metallic ring o' , which is split and has the bolt o^3 passing through the projections o^2 on said ring, so that the ring o' may be tightened upon the projection o .

Connected to the metal ring o' at the point P is the frame of the throwing apparatus. By loosening the bolt o^3 the metal ring o' is loosened from its connection with the projection o and may be turned upon the base O , and the throwing arm may thus be placed at any horizontal angle, and by turning the bolt it can be secured in any one of the desired horizontal positions.

Having now fully described our invention, what we claim, and desire to protect by Letters Patent, is—

1. In combination, a throwing-arm, a chuck consisting of two jaws pivoted together, said chuck being pivoted to the throwing-arm, a cam, substantially as described, connected to the jaw of the chuck, and a cam, substantially as described, upon the throwing-arm in the path of movement of the cam on the chuck, and means, substantially as described, to cause the throwing-arm to operate.

2. In combination, a throwing-arm, a chuck consisting of two jaws pivoted together, said chuck being pivotally connected to said throwing-arm, a cam connected to the jaw of the chuck, said cam being provided with a curved and a notched or recessed portion, and a cam connected to the said throwing-arm in the line of movement of the cam connected to

the chuck, said cam being provided with a curved portion and an angular or projecting portion, and means, substantially as described, to cause the throwing-arm to operate.

3. In combination, a throwing-arm, a chuck consisting of two jaws pivoted together, said chuck being pivotally connected to the throwing-arm, a cam connected to the jaw of the chuck, said cam being provided with a curved portion and a notched or recessed portion, a cam adjustably connected to said throwing-arm in the line of movement of the cam upon the chuck, said cam being provided with a curved portion and an angular portion, and means, substantially as described, to cause the throwing-arm to operate.

4. In combination, a throwing-arm, a chuck consisting of two jaws pivoted together, a spring connecting the outer ends of said jaws, said chuck being pivotally connected to the throwing-arm, a cam connected to the jaw of the chuck provided with a curved portion and a notched or recessed portion, and a cam connected to said throwing-arm in the path of movement of the cam connected to the chuck, said cam being provided with a curved portion and an angular or projecting portion, and means, substantially as described, to cause the throwing-arm to operate.

5. In combination, a throwing-arm, a chuck consisting of two jaws pivoted together, a spring connecting the outer ends of said jaws, said chuck being pivotally connected to the throwing-arm, a cam connected to the jaw of the chuck provided with a curved portion and a notched or recessed portion, a cam adjustably connected to said throwing-arm in the line of movement of the cam connected to the chuck, said cam being provided with a curved portion and an angular or projecting portion, and means, substantially as described, to cause the throwing-arm to operate.

6. In combination, a throwing-arm A , a chuck pivoted to the throwing-arm, said chuck consisting of the jaws d and d' , pivoted together, a spring d^2 , connecting the outer ends of said jaws, a cam F , connected to the jaw d' , said cam consisting of a curved portion and a notched or recessed portion, a cam E in the line of movement of said cam F , a slot in said cam, a screw or bolt connected to said throwing-arm, the head of said screw or bolt passing through said slot in the cam E , said cam E consisting of the curved portion e^2 and the angular or projecting portion e^3 , and means, substantially as described, to cause the throwing-arm to operate.

7. In combination, a throwing-arm, a latch pivoted to the frame, a spring g^6 , connected to said latch, said latch having a bifurcated projecting end of sufficient length to project into the path of movement of the throwing-arm, an arm pivoted to the frame, said arm being in the path of movement of said latch,

whereby when the throwing-arm is moved to lock the trap the latch is forced beyond the pivoted arm, preventing a return movement of the throwing-arm until the pivoted arm is moved out of the way.

8. In combination, a throwing-arm, a latch pivoted to the frame, a spring g^6 , connected to said latch, said latch having the bifurcated end $g\ g'$ and tail-piece g^5 , the end g being in the path of movement of the throwing-arm, an arm h , pivoted to the frame so as to be in the line of movement of the latch, whereby when the throwing-arm is moved to lock the trap the latch is forced beyond the pivoted arm h , preventing a return movement of the throwing-arm until the pivoted arm is moved out of the way.

9. In combination, a throwing-arm, a latch pivoted to the frame, a spring g^6 , connected to said latch, said latch being provided with the bifurcated end $g\ g'$ and the tail-piece g^5 , the end g being in the line of movement of the throwing-arm, an arm h , pivoted to the frame, said arm being in the line of movement of the tail-piece of the latch, a rod, a coil-spring surrounding said rod, said spring being in the line of movement of the arm h , whereby when the throwing-arm is moved to lock the trap the latch is forced beyond the pivoted arm, preventing a return movement of the throwing-arm until the pivoted arm is moved out of the way.

10. In combination, a throwing-arm, a latch pivoted to the frame, a spring g^6 , connected to said latch, said latch being provided with the bifurcated end $g\ g'$ and tail-piece g^5 , a pin g^4 upon said tail-piece, the end g being in the line of movement of the throwing-arm, an arm h , pivoted to the frame, said arm being in the line of movement of the tail-piece of the latch, a rod, a coil-spring surrounding said rod, said spring being in the line of movement of the arm h , whereby when the throwing-arm is moved to lock the trap the tail-piece of the latch is forced beyond the pivoted arm, preventing a return movement of the throwing-arm until the pivoted arm is moved out of the way.

11. In combination, a throwing-arm, a latch pivoted to the frame, a spring g^6 , connected to said latch, said latch being provided with the bifurcated end $g\ g'$ and tail-piece g^5 , a pin g^4 upon said tail-piece, the end g being in the line of movement of the throwing-arm, a spring, one end connected to the latch, the other end to the frame, an arm h , pivoted to the frame, said arm being in line of movement of the tail-piece of the latch, a rod, a coil-spring surrounding said rod, said spring being in the line of movement of the arm h , whereby when the throwing-arm is moved to lock the trap the latch is forced beyond the pivoted arm, preventing a return movement of the throwing-arm until the pivoted arm is moved out of the way.

12. In combination, a throwing-arm, a latch

pivoted to the frame, a spring g^6 , connected to said latch, said latch having a bifurcated projecting end in the path of movement of the throwing-arm, an arm pivoted to the frame in the path of movement of said latch, an electro-magnet, said pivoted arm being connected to the armature of said magnet, a source of current-supply, and connection between the magnet and source of current-supply, the combination being constructed and operating substantially as described.

13. In combination, a throwing-arm, a latch pivoted to the frame, a spring g^6 , connected to said latch, said latch having the bifurcated end $g\ g'$ and tail-piece g^5 , the end g being in the line of movement of the throwing-arm, an arm h , pivoted to the frame, said arm being in the line of movement of the latch, an electro-magnet, said pivoted arm being connected to the armature of said magnet, a source of current-supply, and connection between the magnet and source of current-supply, the combination being constructed and operating substantially as described.

14. In combination, a throwing-arm, a latch pivoted to the frame, a spring g^6 , connected to said latch, said latch being provided with the bifurcated end $g\ g'$ and the tail-piece g^5 , the end g being in the line of movement of the throwing-arm, an arm h , pivoted to the frame, said arm being in the line of movement of the tail-piece of the latch, a rod, a coil-spring surrounding said rod, said spring being in the line of movement of the arm h , an electro-magnet, said pivoted arm h being connected to the armature of said magnet, a source of current-supply, and connection between the magnet and source of current-supply, the combination being constructed and operating substantially as described.

15. In combination, a throwing-arm, a latch pivoted to the frame, a spring g^6 , connected to said latch, said latch being provided with the bifurcated end $g\ g'$ and tail-piece g^5 , a pin g^4 upon said tail-piece, the end g being in the line of movement of the throwing-arm, an arm h , pivoted to the frame, said arm being in the line of movement of the tail-piece of the latch, a rod, a coil-spring surrounding said rod, said spring being in the line of movement of the arm h , an electro-magnet, said pivoted arm being connected to the armature of said magnet, a source of current-supply, and connection between the magnet and source of current-supply, the combination being constructed and operating substantially as described.

16. In combination, a throwing-arm, a latch pivoted to the frame, a spring g^6 , connected to said latch, said latch being provided with the bifurcated end $g\ g'$ and tail-piece g^5 , a pin g^4 upon said tail-piece, the end g being in the line of movement of the throwing-arm, a spring, one end connected to the latch, the other end to the frame, an arm h , pivoted to the frame, said arm being in the line of move-

ment of the tail-piece of the latch, a rod, a coil-spring surrounding said rod, said spring being in the line of movement of the arm *h*, an electro-magnet, said pivoted arm *h* being connected to the armature of said magnet, a source of current-supply, and connection between the magnet and source of current supply, the combination being constructed and operating substantially as described.

In testimony of which invention we have ^{to} hereunto set our hands, at Philadelphia, Pennsylvania, this 10th day of August, 1889.
